UNITED STATES PATENT OFFICE.

GEORGE B. SNODGRASS, OF OKLAHOMA CITY, OKLAHOMA.

INJECTOR.

Application filed May 23, 1924. Serial No. 715,374.

To all whom it may concern:

Be it known that I, GEORGE B. SNODGRASS, a citizen of the United States, residing at Oklahoma City, in the county of Oklahoma and State of Oklahoma, have invented certain new and useful Improvements in Injectors, of which the following is a specification.

This invention relates to improvements in injectors.

An object of the invention resides in providing an injector having a pump cylinder, mounting a manually operable piston for drawing water in an inlet and forcing the same out of a suitable valve outlet into an annular compression chamber with which communicates a suitable hose for projecting liquid therefrom under pressure, the annular compression chamber being adapted to have a quantity of air therein, which is compressed by the pumping of the water from the cylinder, in order to maintain a constant flow from said hose nozzle.

Another object of the invention resides in providing an injector having a pump cylinder and compression chamber formed in concentric relation to the cylinder, and wherein said parts are formed in cooperating sections adapted to provide ready access to both the pump chamber and the compression cylinder, in order that the parts may be repaired and cleaned.

The invention includes other objects and improvements in the details of construction and arrangement of the parts, which are more particularly pointed out in the following description and claims, directed to the preferred form of the invention, it being understood, however, that various changes in the details of construction and formation of these parts may be made within the scope of the invention as described and claimed.

In the drawing, the figure illustrates a vertical sectional view, through the injector, constructed according to the invention.

The base portion of the injector is indicated at 1, which is formed with a recess 2, having the lower end of semi-spherical form, 50 as indicated at 3, for receiving a ball valve 4, adapted to normally seat over the opening 5, forming an inlet for fluid from the lower end of said body, said ball 4 forming the inlet valve for permitting the inlet of water to the recess 2, and preventing a back flow through the inlet opening 5. The bot-

tom of the base portion 1 is formed with a plurality of radially extending grooves 6, so that when the base is seated in a bucket, pan or the like, fluid may flow through said 60 grooves into the inlet opening 5, and recess 2. The upper end of the base portion 1 is provided with an annular bowl shaped projecting flange 7, which is screw threaded, at the upper free edge thereof as indicated 65 at 8, for receiving the screw threaded flange 9, on the co-operating annular projection 10, from the pump cylinder 11, which is of cylindrical form, as indicated. The lower end of the pump cylinder is provided with screw 70 threads for threaded cooperation with the upper end of the recesses 2 as indicated at 12, the screw threaded connection 8 and 12 serving to mount the sections of the injector in assembled relation.

The cylinder 11 is provided with an internal flange 13, adjacent the lower end thereof, to provide a seat for one end of the coil spring 14, which is normally expandable for removing the piston 15 to the 80 upper end of the cylinder as shown in the drawing, the piston rod 16 mounting said piston being slidably extended through the cap 17, screw threaded on the upper open end of the cylinder 11, and formed with a 85 plurality of openings 18, registering with corresponding openings in the upper ends of the cylinders to permit the intake and exhaust of air above the section, in the reciprocation thereof. The upper ends of the piston rods 16 beyond the cap 17 is provided with a handle 19, so that the same may be grasped for convenient manual operation.

The cylinder 11 is formed slightly below the central portion thereof and in substantially the plane of the lower edge of the annular projection 10 with a shoulder 20, providing a stop, for preventing the movement of the piston 15, below the outlet nipple 21, formed in the cylinders and providing an 100 outlet for the fluid therein, to the annular chamber 22 formed by the cooperation of the annular projections 7 and 10, on the base and cylinder respectively. A suitable valve 23 is mounted on the cylinder 11 for permitting the outlet of fluid from the cylinder, but preventing a back flow into the same.

The annular projecting flange 10 is formed at 24 with a boss of annular form, having a threaded opening for receiving a curved 110 pipe section 25, which extends within the chamber 22, and to a point below the hor-

izontal plane of the outlet 21, while the outer end of the boss 24 receives a flexible pipe connection 26, provided at the free end with a nozzle 27, so that liquid pumped into the 5 chamber 22 may be forced outwardly of said nozzle for projecting in a stream under substantial pressure.

From the foregoing description, it should be readily appreciated that a simple and convenient form of injector has been provided, 10 which may be placed in a bucket or pan of water or the like, and upon the manual operation of the piston 15 in the cylinder, the liquid will be drawn upwardly through 15 the inlet opening 5 into the cylinder, and forced outwardly through the opening 21 into the annular chamber 22, where it will compress the air in the upper portion of the chamber, and through constant reciprocation 20 of the piston will force the fluid outwardly through the nozzle 27, in a stream, under pressure, the compression of the air in the chamber 22 maintaining a constant flow of the fluid, at substantially the same pressure. 25 It will also be noted that the main structure of the injector is included in a pair of co-operating sections, which may be easily assembled or disassembled to permit cleaning and repair of the parts in an obvious manner.

What is claimed is:

1. An injector comprising a base member formed with a recess, and an annular projecting flange, said base also having a 35 valved inlet providing communication with the recess, a cylinder having an annular projecting flange, said cylinder and projecting flange thereon being adapted for cooperation with the recess in the base and the 40 flange of the base member, to provide an as-

sembled injector unit, said cylinder having a valved outlet communicating with the compression chamber formed by the cooperation of the flanges on the cylinder and the base, a hose communicating with said compression chamber, and having a nozzle at the free end thereof, and a piston reciprocable in said cylinder, adapted to circulate fluid into the compression chamber and outwardly of said hose and nozzle.

2. An injector, comprising a base portion having a recess formed therein, an inlet opening communicating with said recess, and an annular bowl shaped flange projecting upwardly from the upper end thereof, a cylinder screw threaded at the lower end for cooperation with the body and communicating with the recess thereof, said cylinder being formed with an annular projecting flange having the free edge thereof adapted for threaded cooperation with the free edge of said bowl shaped flange on the base portion, an outlet opening formed in the cylinder communicating with the chamber formed by said flanges, a piston reciprocable in said cylinder, a pipe mounted in the flange on the cylinder, having the lower end terminating below the outlet opening therein, in the compression chamber, a hose connection communicating with said pipe, and resilient means for normally retaining the piston in the upper end of the cylinder, whereby manual reciprocation of said piston will serve to draw fluid inwardly of the cylinder through said inlet opening to force the same outwardly into said compression chamber, for a subsequent projection outwardly of said hose.

In testimony whereof I affix my signature.

GEORGE B. SNODGRASS.
